DESIGN FOR A TEXTILE FABRIC OR SIMILAR ARTICLE

Application filed January 4, 1933. Serial No. 46,716. Term of patent 3½ years.

To all whom it may concern:

Be it known that I, MACLYN GUHL, a citizen of the United States of America, residing at Sutton Hall, Forest Hills, Long Island, New York, have invented a new, original, and ornamental Design for a Textile Fabric or Similar Article, of which the following is a specification, reference being had to the accompanying drawing, forming a part thereof.

The figure is a plan view of a textile fabric showing one fourth of the unit of my new design. The full lines of the drawing show one eighth of the design in detail, the other

portions indicated in dotted lines being a repetition of the detailed illustrations arranged in proper relation thereto. The other three fourths of the unit are arranged about the common center indicated by the intersecting dot and dash lines in the same relationship as indicated in the illustrated one fourth.

I claim:

The ornamental design for a textile fabric or similar article as shown and described.

In testimony whereof I have signed this specification.

MACLYN GUHL.
